UNITED STATES PATENT OFFICE.

BERNARD F. GREEN, OF DUBUQUE, IOWA.

AWNING MANIPULATOR.

Application filed November 15, 1926. Serial No. 148,599.

My invention relates to pulleys and more particularly to that class employed in connection with the operation and manipulation of awnings. The principal object of the invention is to provide a compact, simple and easily adjustable device of this character capable of operating in a manner such that the friction usually generated between an awning cord or string and its cooperating fixture is reduced to a minimum. A further object of the invention is to construct a device which may be readily installed without the aid of cumbersome wall attachments.

A primary feature of the invention consists in providing, in combination with a ring-like member having a threaded projection, a rotatable pulley disposed within said member, and a frame for supporting said pulley, the said frame being pivotally secured to the said member.

A further feature of the invention resides in fashioning a screw eye with a plurality of oppositely extending studs and in associating therewith a plurality of means respectively mounted on said studs, each of said means involving a rotatable pulley and a frame constituting a support for the latter.

Other features of the invention pertaining to advantageous forms of construction and combinations of parts will hereinafter appear and be pointed out in the claims.

In the drawings,—

Figure 1 is a plan view of a device embodying my invention.

Figure 2 is a detail sectional view illustrating the manner of pivotally connecting the pulley frames to the screw eye.

Figure 3 is a view similar to Fig. 1, the device as shown being provided with only one pulley.

In the drawings, 1 indicates a ring-like member fashioned with a threaded projection 2, the latter forming means for effectively attaching the ring member to any desired support. As is well known, the parts 1 and 2 constitute what is commonly termed a screw eye. Opposite the threaded projection 2, the ring-like member is provided with a portion 3 of preferably rectangular cross section, thus presenting a plurality of substantially flat surfaces 4.

A plurality of pulley frames 5 are respectively pivotally connected to opposite faces of the rectangular portion 3 of the ring member 1 in a manner such that one of said frames is disposed within and encompassed

by the ring, the pivotal axis of both of said frames being substantially normal to the axis of the ring. These frames are respectively pivotally connected to the ring member by studs 6 which are disposed substantially centrally of and project from the aforementioned flat surfaces 4, the studs being advantageously formed integrally with the member 1. The outer ends of the studs 6 are upset as 65 at 7 to prevent the frames 5 from becoming accidentally disconnected therefrom. To obviate undue wear between the frames and ring 1 washers 8 are preferably interposed therebetween.

Rotatably journaled in the frames by means of pins 9 having enlarged or upset ends 10 are pulleys or rollers 11, each of which is fashioned with a concave periphery 12 to accommodate the usual awning cord or string 75 (not shown). As illustrated in Fig. 3, in cases where it is not required the pulley and its cooperating stub which is located without the ring 1, may be readily discarded.

The devices as illustrated are preferably designed to be attached or secured by the threaded projection 2 to a wall or other means of support so that the pivotal axis of each of the pulley frames 5 is substantially vertical or, in other words, so that the axis of rotation of the pulleys is substantially horizontal. By this arrangement it will be appreciated that the pulleys will respond to the pressure applied to them by the awning cord or the like so as to readily adjust themselves 90 and assume a position such that the awning may be operated with a minimum of effort. This free and automatic adjustment of the pulleys in response to force applied thereto by the awning cord obviates the great waste 95 of cord occasioned by drawing the latter over relatively stationary or immovable parts.

In addition to the office of support, the screw eye affords simplicity of adjustment 100 and dispenses with cumbersome wall attachments heretofore employed in connection with pulleys of any description.

I claim:—

1. In a device of the character described, 105 the combination with a ring-like member having a threaded projection, of a rotatable pulley disposed within said member, and a frame for supporting said pulley, said frame being pivotally secured to the said member. 110

2. In a device of the character described, the combination with a ring-like member

having a threaded projection, of a rotatable pulley disposed within said member, and means pivotally connecting the said pulley to the said member, the axis of the latter being substantially normal to the pivotal axis of said means.

3. In a device of the character described, the combination with a ring-like member having a threaded projection, of a rotatable pulley disposed within said member, a frame for supporting said pulley, and means integral with said member for pivotally connecting the frame to said member.

4. In a device of the character described, the combination with a ring-like member having a threaded projection, a portion of the inner surface of said member being substantially flat, of a rotatable pulley disposed within said member, and a pivotally mounted frame for supporting said pulley, the flat

portion of said member being formed with means for pivotally connecting the frame to the latter.

5. In a device of the character described, the combination with a screw eye having a rotatable pulley disposed therein, of a frame for supporting said pulley, said eye being provided with an inwardly projecting stud constituting means for pivotally connecting the said frame to the eye. 30

6. In a device of the character described, the combination with a ring-like member having a threaded projection and being fashioned with a plurality of oppositely extending studs, of a plurality of means respectively mounted on said studs, each of said means involving a rotatable pulley and a frame constituting a support for the latter. 35

In testimony whereof I affix my signature.

BERNARD F. GREEN.
